UNITED STATES PATENT OFFICE.

GRANVILLE T. WOODS, OF NEW YORK, N. Y., ASSIGNOR TO THE UNIVERSAL ELECTRIC COMPANY OF THE CITY OF NEW YORK.

ELECTRIC-RAILWAY CONDUIT.

SPECIFICATION forming part of Letters Patent No. 509,065, dated November 21, 1893.

Application filed October 14, 1892. Renewed September 26, 1893. Serial No. 486,483. (No model.) Patented in Canada February 4, 1893, No. 41,803.

To all whom it may concern:

Be it known that I, GRANVILLE T. WOODS, a citizen of the United States, residing in New York, county and State of New York, have 5 invented certain new and useful Improvements in Electrical Railways, (for which I have received Letters Patent in Canada, No. 41,803, dated February 4, 1893,) of which the following is a specification.

10 My invention relates to that class of electric railroads having underground conduits in which the contact devices are contained and operated.

The object of the invention is to provide a 15 system that may be economically installed and operated and in which loss of current due to leakage, as well as the element of danger where high tension currents are employed, may be practically eliminated. To this end 20 I employ a conduit of any ordinary construction that may as usual be located between the rails of the track. Within this conduit or suitably contiguous thereto the insulated lead or leads of the circuit may be located. At intervals 25 I support within the conduit closed contact boxes with each of which the circuit is connected, the connection being led into the interior of the box to a contact plate or device therein, all exterior connections being

30 completely insulated. The boxes are provided with a projecting insulated switch arm or contact closing device normally lying in the path of a brush or contact plate carried by the car, by means of which the insulated contacts within the box are brought together and the circuit completed through the motor on the car. There are therefore no uninsulated or exposed conductors within the conduit, and the motor on the car is only connected 35 40 with the circuit while the brush carried thereby is bearing against the switch arms of the contact boxes. There is, therefore, no possibility of leakage except during this brief period; and to prevent leakage during such

45 time each box is charged with oil and is provided with a porous portion or wall through which the contained oil gradually percolates keeping the exterior of the box and the parts connected therewith coated with a layer or 50 film of oil that prevents the deposit or con-

densation of moisture thereon. The box is completely charged with oil and the contacts therein through which the connection of the motor on the car with the main circuit is completed, are immersed in oil.

55 In order to obviate the necessity for examination and periodic filling of the boxes I connect each box with a pipe system containing oil under pressure. This not only insures that the boxes shall be completely filled at 60 all times, but the pressure causes the oil to penetrate the porous medium of the boxes and maintain their exterior parts and connections constantly covered with oil. In connection with this organization I employ a brush or 65 contact device carried by the car that always insures the opening of the circuit at the brush before the circuit can be opened at the contacts within the boxes. I thus prevent the formation of a spark within the boxes and the 70 consequent destruction of the contacts and carbonization of the oil, so that when the system is once installed, the boxes and circuit connections therein will require no attention for an indefinite period, while the switch arm 75 of the box and the brush carried by the car may be renewed or repaired as occasion may require.

My invention, as well as the details of construction, is more fully hereinafter set forth, 80 and also shown in the accompanying drawings in which—

Figure 1 is a rear elevation of the car and a view of the track, roadbed, and conduit in cross-section; Fig. 2 a vertical central section 85 through one of the boxes; Fig. 3 a bottom view thereof with the bottom plate removed; Fig. 4 a diagram of the system; Fig. 5 a detail diagrammatic view illustrating the arrangement and action of the brush or contact 90 plate carried by the car; Fig. 6 a transverse longitudinal section through such a brush; and Fig. 7 a face view thereof.

Of course in this system both leads or sides of the main circuit may be insulated and connected with opposite series of boxes in the conduit as above suggested, or there may be one insulated lead, one series of boxes and the track may constitute the other side of the circuit.

In Fig. 1, A indicates the hanger on the car carrying the brush or contact plate B, and C C indicate a pair of contact boxes arranged on opposite sides of the conduit and supported upon the wall thereof in any suitable manner, D being the switch or contact arms of the boxes against which the brush B works.

In Fig. 4, G is the generator and G' G' the insulated leads or sides of the circuit thereof. 10 Each box C is connected with the circuit by an insulated connection g g.

P indicates a pump and P' P' the opposite sides of a pipe system into which oil or other fluid insulating material is forced under 15 pressure by the pump. The interior of each box C is connected with each side of the pipe system by a branch pipe p, which may be provided with a cock p'.

B is the brush carried by the car, D the 20 switch arms of the boxes and M the motor on the car.

The boxes are shown in detail in Figs. 2 and 3. They may consist of a casting C' open at both ends and having about midway of its 25 length an internally projecting flange c and two hubs or tubular projections, one p² for the connection of the oil pipe p, and another g' for the connection of the insulated branch conductor g. One half of the box, that is, the 30 upper half as seen in Fig. 2 may be annular while the lower half below the flange c may be semi-circular on one side and have a right angular extension C² from the other. This end of the box may be closed by a cap or lid 35 C³ tightly secured by means of bolts passing through lugs or ears thereon or otherwise. The projecting hub g' is shown as formed upon the square projection at the box and instead of extending out at right angles from 40 the wall thereof it is preferably curved downwardly as indicated. The interior bore thereof is preferably larger than the opening g² in the end thereof and the opening g³ leading into the box, so that when the insulated conductor g is inserted asphaltum or 45 other heated insulating material g⁴ may be poured in. Of course any suitable way of leading in the conductor and sealing the entrance may be adopted. The end of the conductor within the box carries or is connected 50 to a contact plate H having two projecting ends h between which works a contact arm I carried on the end of a rod or shaft I' extending up through the box. This rod may 55 be supported and provided with a bearing as follows: Beneath the flange c is placed a plate K of wood or other insulating material. Above the flange is a similar plate K', on which is placed a relatively thick washer or mass of 60 porous insulating material K², such for instance, as asbestos, earthenware or other suitable material, fibrous or otherwise. Above the washer is another plate K³ of insulating material. A flanged sleeve L is passed 65 through the plates K, K', K², K³ the flange abutting against the lower plate K, and is provided at the top with a screw clamp nut

L'. The rod I' has its bearing within the sleeve L and upon its inner end carries the contact arm I which is provided with a tubular hub fitting upon and secured to the end of the shaft and having a flange between which and the flange of the sleeve L, a packing washer i is placed. This is for the purpose of preventing an excessive leak of oil along 70 the shaft or rod I'. The laterally projecting switch or contact arm D may be composed, as shown of two plates of metal lying against each other and secured to the outer end of the shaft I'. These plates are preferably of spring 80 metal, such for instance as tempered brass, copper or other metal, or compositions of metals. Its short end is connected with one end of a spiral spring enveloping the shaft and having its other end connected with the clamp 85 nut L'. When therefore the switch arm D is operated as presently described, there are two yielding or resilient connections, one the arm D itself, the other the spiral spring, and a third may, if desired be provided by also making the interior contact arm I elastic. This 90 prevents the jarring of the box, its supports and electrical connections when the brush on the car comes in contact with and leaves the switch arm D. Oil from the connection p² is 95 introduced into the large end of the box and finding its way through and past the insulating plates K, K', percolates through the porous medium K² and past the plate K³ to the top of the box. I prefer that there shall be 100 an accumulation of the oil here, and for this purpose the upper edge or wall of the box is caused to project above the level of the clamping nut L' and also preferably above the end 105 of the sleeve L, so that there is a perfect protection against moisture entering along the bearing of the shaft I', and a thorough lubrication of its bearing is insured. The seeping of the oil up through the box is preferably so controlled that there is but a slight discharge 110 over the edge of the box that will be only sufficient to keep the walls and bottom of the box and the insulation of the conductor g coated with a suitable film of oil. A receptacle may, however, if desired be placed within 115 the conduit beneath each box to collect such dripping of the oil as may occur, and from which the collected oil may from time to time be pumped or otherwise withdrawn.

The details of construction which I have 120 shown and described are suitable practical and efficient, but I do not limit myself to them as obviously they might be varied in many ways. The strain of the spiral spring around the shaft I' that occurs when the arm 125 D is struck and strained to one side by the brush on the car should preferably be in a direction tending to screw up the nut. When thus arranged there is no liability of the nut becoming loose. The nut may also be pinned 130 to the washer K³. As shown in Fig. 4 the boxes on opposite sides of the conduit are arranged in alternation and the brush B is of a sufficient length to be always in contact with

at least two of the switch arms D on opposite sides of the conduit. I prefer as shown in the diagram to employ opposite series of boxes and to insulate both leads of the circuit, but the principles of my invention may as before stated be employed in a system where the rails form one side of the circuit. In such an organization the brush B should be long enough to be always in contact with the two switch arms D. The character of the brush that I prefer to employ is shown in detail in Figs. 5, 6, and 7, in which *x* represents one of the rails of the track and *y* one of the walls of the conduit slot.

15 A are the hangers from the cars carrying the brush B, C the boxes, D their contact arms, G' one of the insulated leads of the circuit and *g* the insulated branches leading into the boxes. The pipe connections for the 20 oil circulation are omitted. In this case the brush is composed of a body of insulating material *b*, upon which the contact plate *b'* is connected with the motor on the car is mounted. The ends of the plate *b'* do not 25 extend to the end of the body *b*, but there is at each end of the brush a face of insulating material as seen in Fig. 5, extending beyond the end of the contact plate *b'*. These insulated faces at each end are preferably below 30 or inside of the plane of the face of the contact. In these figures the contact boxes are indicated as being upon one side only of the conduit. As the car traverses the track, the brush successively strikes the laterally projecting switch arms D which bend and are 35 moved to one side as indicated in Figs. 4 and 5. The shaft I' partially turned in its bearing and the contact arm carried thereby, is pressed against one of the contact plates *h* 40 of the main line contact. The brush contact *b'* establishes a good rubbing connection with the switch arms D and the circuit is completed through the motor on the car. As the brush leaves a switch arm D the arm passes off 45 of the contact plate *b'* with an abrupt snap motion on to the insulated face extending beyond the end of the contact. The main circuit is therefore opened at this point, and the connection within the box cannot be broken until the 50 switch arm runs off of the insulation *b*. Of course the operation is precisely the same where boxes are arranged on each side of the conduit, the brushes B then having contact plates *b'* on each side of and insulated end portions on each side as already described. 55 In the event of the backing of the car the switch arms D, as seen for instance in Fig. 4, that are bearing against the brush contact plates *b'* will maintain their positions, as is 60 obvious, and there will therefore be no opening of the circuit within the boxes, the switch arms being still held in their positions after they have run off on to the insulated end portion *b*. Were it not for the fact that the insulated part of the brush extends beyond the contact plates, there might be a breaking of the circuit within the box after the brush has

passed from the switch arm and the arm by reason of its resiliency follows up the receding brush. If at this time the arm were in 70 electrical connection with the contact plate of the brush the circuit would first be open at the contacts within the box, but with the organization described, the circuit will have already been open when the switch arm leaves 75 the contact plate of the brush and bears upon the insulation end thereof. By providing a brush therefor with an insulated extension beyond each end of the contact plate the circuit must always be broken at the brush and 80 there is no liability of the circuit first being broken in the box. In order to prevent wear and maintain the surfaces of the switch arm clean and well polished, the ends of the brush may have inserted into the insulation metal 85 plates *b'* which are however, entirely insulated from the contact plates of the brush. Where the boxes are arranged on both sides of the conduit the brushes shown in Figs. 5, 6 and 7 would of course have contact plates on each side. 90 This construction is indicated in the diagram Fig. 4. In my organization the boxes are arranged at the side of the conduit and not beneath the slot. The contact devices of each box are controlled by a partially rotatable shaft 95 having its bearing in the box. This enables me to practically hermetically close the box so far as the shaft opening is concerned since it may be very effectively packed. The switch contact arm that operates the shaft is itself 100 operated by the vertical face of the shoe working against the vertical face of the head or end of the switch arm. There is therefore little liability of such contact faces becoming covered with mud, dirt, snow or ice, and they 105 are kept burnished by the rubbing contact between them.

I claim as my invention—

1. In an electric railroad system, the combination of the insulated lead or leads of the 110 main circuit, a series of boxes having interior contact devices with which the main circuit is connected, each box being charged with oil or other insulating fluid in which the contacts are immersed and having a porous medium or portion through which the oil exudes 115 and coats the exterior of the box and its connections, and a switch arm carried by the box and controlling the inclosed main circuit contacts and adapted to be operated by a contact brush or device carried by the passing car.

2. In an electric railroad system, the combination of the lead of the main circuit, a conduit, a series of closed boxes arranged there-in, contact devices within each box with which said lead is connected, a shaft having its bearings in the box and carrying a contact arm within the box that works against said contact devices when the shaft is partially rotated, the switch arm carried by the outer end of said shaft adapted to be operated by the brush of the passing car to complete the 125 main circuit through the motor thereon, a

- pipe system for distributing oil or other insulating fluid under pressure and connections between said system and the interior of the boxes.
- 5 3. In an electric railway, the combination with the track and slotted conduit, of a series of closed boxes arranged therein to one side of the slot and containing an insulated contact device with which the lead of the circuit is connected, an upright shaft having its bearing in each box, the shaft being partially rotatable to complete the circuit from said contact device through the shaft, a switch contact arm projecting laterally from each shaft 15 toward the center of the conduit and having a vertical contact face, and a contact shoe having an elongated smooth vertical contact face carried by a car, the organization being such that the switch contact arms are struck by the elongated vertical face of the contact shoe and the shafts partially rotated, thereby successively completing the circuit through the motor on the car, substantially as set forth.
- 25 4. In an electric railroad system, the combination of the lead or leads of the main circuit, a conduit, a series of boxes arranged therein, contact devices within the boxes, with which said lead or leads are connected, the switch 30 or contact arms of the boxes adapted to be operated by the brush of the passing car to complete the main circuit through the motor thereon, a pipe system for distributing oil or other insulating fluid under pressure and connections between said system and the interior of the boxes, each box having a porous medium or portion through which the oil filtrates and coats the exteriors of the boxes and their connections.
- 35 5. In an electric railroad system, the combination with the conduit of a series of boxes located therein and containing oil or other insulating fluid therein under pressure, the insulated lead or leads of the main circuit connected with contact devices within the 40 boxes submerged in the oil, and contact controlling devices adapted to be actuated by the brush or contact device on the passing car to complete the circuit through the motor 45 thereon, each box having a porous medium or portion through which the oil filtrates and coats the exterior of the box and its connections.
- 50 6. In an electric railroad system, the combination of the lead or leads of the main circuit, the conduit, a series of closed boxes arranged therein having interior contact devices connected with the lead or leads, laterally projecting yielding switch arms, and a brush 55 carried by the car, the brush having a contact face or faces against which the switch arms work and insulation extending beyond the ends of the contact faces for the purpose set forth.
- 60 65 7. In an electric railroad system, the combination of the lead or leads of the main circuit, the conduit, a series of closed boxes arranged

therein having interior contact devices connected with the lead or leads, laterally projecting yielding switch arms, and the brush 70 carried by the car, the brush having a contact face or faces against which the switch arms work and insulation extending beyond the ends of the contact faces, and the boxes being filled with oil, for the purpose set forth. 75

8. In an electric railroad system, the combination of the lead or leads of the main circuit, the conduit, a series of closed boxes arranged therein having interior contact devices connected with the lead or leads, laterally projecting yielding arms, and the brush carried by the car, the brush having a contact face or faces against which the switch arms work and insulation extending beyond the ends of the contact faces, and the boxes filled with 85 oil, and having a porous medium or portion through which the oil filtrates and coats the exteriors of the boxes and their connections, for the purpose set forth.

9. The combination substantially as set forth, of a conduit, the boxes therein having the yielding switch arms D and the brush to be carried by the car having a contact plate b' which works against and makes contact with the switch arms and insulation extending beyond the ends of the contact plate. 95

10. The combination, substantially as set forth, of a conduit, the boxes therein having the yielding switch arms D and the brush to be carried by the car having a contact plate 100 b' which works against and makes contact with the switch arms and insulation extending beyond the ends of the contact plate, the insulation extension being below or inside of the plane of the surface of the contact. 105

11. The combination of the shell of the box, having two projections or coupling connections, one p' for the connection of an oil supply pipe and one g' for the leading in of a circuit conductor, the contact plate connected 110 with the end of the conductor within the box, the contact arm working against said plate, the shaft or rod to which it is attached, its bearing, the porous packing surrounding the bearing and closing the ends of the box, and 115 the switch arm D carried by the shaft.

12. The combination substantially as set forth, of the box shell, the inwardly projecting flange c, the plates of insulating material and porous packing, the flanged sleeve, the 120 shaft therein, the interior contact arm carried by the shaft, the switch arm carried by its outer end, the clamp nut on the screw and the spring connected with the switch arm and the clamp nut.

13. The combination of the shell of the box, means for maintaining a supply of oil therein, the vertical shaft or rod its bearing within the box and the switch arm carried by the upper end of the shaft the edge of the box being extended up beyond the bearing of the shaft to form a receptacle and oil filling said receptacle, all substantially as and for the purpose set forth. 125 130

14. The combination of the box, the yielding or spring switch arm, D, its rod or shaft, having its bearings in the box the spring that holds the shaft in the normal position, the contact arm carried by the shaft within the box, and the contact plate within the box to which the insulated circuit wire is connected.

15. In an electric railroad, the combination of the contact devices arranged at intervals along the line of the road, a switch arm controlling each of them, and a brush carried by a car and adapted to operate the switch arm, to close the circuit at the contact devices and

between the brush and switch arm, the brush consisting of insulating material and a contact plate beyond both ends of which the insulation extends, whereby as the car passes the circuit is first broken at the switch arm and brush and then at the said contact devices, substantially as set forth.

In testimony whereof I have hereunto subscribed my name.
